Primary Examiner — Jennifer Rivard*(74) Attorney, Agent, or Firm* — Dan De La Rosa(57) **CLAIM**

We claim the ornamental design for a shaving device, as shown and described.

DESCRIPTION

FIG. 1 is a front perspective view of a shaving device shown with the cap of the present invention showing our new design;

FIG. 2 is a front side elevation view thereof;

FIG. 3 is a back side elevation view thereof;

FIG. 4 is a side elevation view thereof;

FIG. 5 is another side elevation view thereof;

FIG. 6 is a top plan view thereof;

FIG. 7 is a bottom plan view thereof;

FIG. 8 is a perspective view of the shaving device shown without the cap;

FIG. 9 is a front side view of FIG. 8;

FIG. 10 is a back side view of FIG. 8;

FIG. 11 is a side view of FIG. 8;

FIG. 12 is another side view of FIG. 8;

FIG. 13 is a top plan view of FIG. 8; and,

FIG. 14 is a bottom plan view of FIG. 8.

The shaving device is shown with and without the cap for convenience of illustration.
